United States Patent Office

Des. 185,503
Patented June 16, 1959

185,503

LAVATORY FITTING OR SIMILAR ARTICLE

Herbert V. Kohler, Kohler, Wis., assignor to Kohler Co.,
Kohler, Wis., a corporation of Wisconsin

Application January 9, 1959, Serial No. 54,107

Term of patent 14 years

(Cl. D91—3)

Fig. 1

Fig. 2

Fig. 3

Fig. 4

Fig. 5

Fig. 1 is a perspective view of a lavatory fitting showing my new design;

Fig. 2 is a side elevational view of the same;

Figs. 3 and 4 are elevational views of the front and rear of the fitting, respectively; and

Fig. 5 is a top plan view of the lavatory fitting.

The dominant features of the design reside in the portions shown in full lines.

I claim:

The ornamental design for a lavatory fitting or similar article, as shown and described.
